UNITED STATES PATENT OFFICE

92,545

DESIGN FOR A LAMP SHADE

Millie Moss, Huntington, W. Va.

Application March 20, 1934, Serial No. 51,113

Term of patent 3½ years

To all whom it may concern:

Be it known that I, MILLIE MOSS, a citizen of the United States, residing at Huntington, in the county of Cabell and State of West Virginia, have invented a new, original, and ornamental Design for a Lamp Shade, of which the following is a specification, reference being had to the accompanying drawing, forming part thereof.

I claim:—

The ornamental design for a lamp shade as shown.

MILLIE MOSS.
